UNITED STATES PATENT OFFICE.

JAMES E. SEELEY, OF LOS ANGELES, CALIFORNIA, ASSIGNOR TO HIGH FREQUENCY IGNITION COIL COMPANY, OF LOS ANGELES, CALIFORNIA, A CORPORATION OF CALIFORNIA.

IGNITION SYSTEM.

1,015,089.

Specification of Letters Patent.

Patented Jan. 16, 1912.

Application filed November 28, 1910. Serial No. 594,597.

To all whom it may concern:

Be it known that I, JAMES E. SEELEY, a citizen of the United States, residing at Los Angeles, in the county of Los Angeles and 5 State of California, have invented a new and useful Ignition System, of which the following is a specification.

This invention relates to means for interrupting the circuit of sparking devices 10 for internal combustion engines, and for distributing the sparking current to the respective cylinders of the engine.

The main object of the invention is to provide for giving breaks in rapid succession, as required, for example, in multicylinder engines, and at the same time allow for maximum energization of the self-inductive means from which the energy of the spark is derived.

20 Another object of the invention is to extend the range through which the spark may be advanced, while at the same time providing sufficient duration of contact for effectual energization of the induction 25 means.

The ignition system comprises a source of electric current, a charging circuit connected thereto and including self-induction means, an interrupter and a distributer, a condenser 30 connected to said circuit, discharge circuits connected to said distributer whereby the energizing circuit is brought successively into connection with said discharge circuits and is interrupted during such time of connection so as to cause the condenser to be charged and to discharge through each discharge circuit, and means for providing a supplementary energizing connection for the charging circuit, before connection is 35 made to the discharge circuit.

In a multicylinder engine, the time during which the distributer contact is connected to any particular discharge circuit is limited more or less according to the speed 45 of the engine and to the number of segments required for the several cylinders.

In the regulation of the engine it is required to advance the spark as the engine speeds up and in doing so the time of break 50 at the interrupter is shifted relatively to the motion of the distributer contacts, and the time during which the distributer is establishing connection through the energizing circuit is correspondingly reduced, and with 55 high speeds and with more than two cylin-

ders the reduction of time is such that the energizing circuit does not have opportunity to be fully energized. To obviate this difficulty I provide for energizing the charging circuit by a supplementary connection independently of the segment on which the discharge takes place, so as to enable energization of the charging circuit without interfering with the selection of the discharge circuits by the distributer.

60 The accompanying drawings illustrate the invention, and referring thereto: Figure 1 is a transverse section of the device on the line x^1-x^1 in Fig. 4, showing the interrupter in open position. Fig. 2 is a similar 65 view, showing the interrupter in closed position. Fig. 3 is a section on line x^3-x^3 in Fig. 4. Fig. 4 is a longitudinal section of the device. Fig. 5 is a longitudinal section of a self-inductive coil provided on the rotatable member of the device. Fig. 6 is a 70 diagram of the circuit connections.

The circuit controlling device comprises a socket or attaching portion 1 adapted to fit over the operating shaft, indicated at 2, 75 and to be secured thereto by screw means 3, interrupting devices carried by said attaching means so as to rotate with the said shaft and an inclosing case rotatably mounted on 80 said attaching means and carrying the terminals for the distributer and provided with controlling means for advancing the spark.

The inclosing case referred to comprises a cylindrical member or ring 4 of insulating material, a tubular metal extension 5 at the 85 inner end of said ring rotatably mounted on the member 1 by ball bearings 6 and an outer or cover member 7 secured to the outer end of the ring 4 and formed with a bearing 8 for an arbor 9 to which is secured by screw 90 means 10 a lever 11 provided with means 11' for attachment to the rod leading to any suitable means for manual operation to control the time of interruption. The inner end of the arbor 9 is provided with an enlarged head 12 formed with an inwardly extending lug 13 to engage a fixed or cam member of the interrupter and control the angular position thereof.

100 The interrupter is mounted on a cylindrical block 15 secured to the supporting or attaching member 1 and rotating therewith. Said cylindrical block 15 is of insulating material and a metal plate 16 secured thereto carries a vibratory member 17 mounted 105 110

by pivot 18 on said plate 16 and provided with a contact 20 at its outer end adapted to make and break with a contact 21 screwing into a metal bracket 22 secured to the 5 cylindrical block 15. A spring 24 secured to a metal plate 16 and the vibratory member 17 tends to hold the contact arm at member 17 in position to close the circuit at 20, 21, said arm 17 being provided with a projection 25 adapted to be engaged by cam means 26 to move the said contacts into closed position. Said cam means consists of a cylindrical metal body rotatably mounted on a stud 27 extending from and connected 10 to the metal plate 16, said cylindrical body having a plurality of longitudinal grooves 28 forming cam surfaces for engagement with and operation of the projection 25, as stated. A metallic pin 30 mounted to slide 15 longitudinally in the arbor 9 engages with the end of the stud 27, being pressed into such engagement by a spring 31 contained within a longitudinal bore in said arbor 9, a plug 32 screwing into said bore engaging 20 the outer end of said spring to control its pressure. A metal strip 23 connects arm 17 with the plate 16, serving as a conducting bond.

The distributor means comprises a fixed 30 member consisting of the insulating ring 4 aforesaid and an annular series of metallic contacts 35 carried thereby, and a movable member consisting of a contact 36 radially slidable in a slot 37 formed in a sleeve 38 35 extending transversely in the cylindrical body 15, a spring 39 engaging said contact 36 to press the same outwardly, the further end of said spring abutting against contact means for completing the circuit. In connection with the distributor, I provide a self-induction coil 40, said coil being preferably mounted in the rotary member of the distributor to rotate therewith and being preferably located so that the spring 39 40 aforesaid contacts with the outer casing 41 of said coil, said coil being an iron-clad coil with iron casing 41 and iron core 33 with non-magnetic and non-conducting heads 42 at the ends thereof. The core member 45 of said coil is fastened by a screw 43 screwing into a metal plate 44 attached to the supporting member 1 and supporting the insulating cylinder 15 and the parts carried thereby. The coil 40 is connected at one end to the outer casing 41 so as to be in conductive connection with the distributor contact 36, and the inner end of said coil is connected to the core 33, which through the screw 43, is in conductive 50 connection to the plate 44, constituting a "ground" connection.

Referring to Fig. 6, the circuit connections for the above described circuit controlling device are as follows: The shaft 2 55 and the parts in metallic connection there-

with are grounded as indicated at 34. The self-induction coil 40 above referred to is grounded as above stated at one end, the other end of said coil being connected as described, to the rotary distributor contact 36. Said rotary distributor contact 36 is also connected by a bond 45 to the fixed contact 21 of the interrupter. The movable contact of the interrupter indicated at 20 is connected by the contact means 31 and 32 to binding screw means 10. The main energizing circuit 48 is connected to this binding screw means and includes a self-induction or inductance coil 49 and a switch 50, whereby it may be connected to a battery 51 or to a magneto 52, grounds 53 and 54 being provided for these sources of current, to complete the circuit. A condenser 55 is connected at one side to the circuit 48 and at the other side to ground as at 56. A connection 57 leads from each distributor contact 35 to a primary coil 58 of a high tension induction coil, the other end of said primary coil being grounded as at 59 and the secondary 60 of said induction coil being connected at one end to the connection 57 and at the other end to an electrode 61 of a spark gap device, the other electrode of which is grounded in the usual manner by connection with the body of the engine. 95

The operation is as follows:—Assuming that the switch 50 is moved to close the connection from battery 51 to the charging circuit 48, current will pass from said battery through said switch and circuit 48, including the self-induction coil 49 therein, to connection means 10, 32, 31, pin 30, pivot 18, plate 16, arm 17, and movable contact 20, and when the interrupter is in position shown in Fig. 2, the circuit is continued from contact 20 to fixed contact 21, bond 45, sleeve 38 to the movable contact 36 of the distributor. When the said movable contact is in contact with any one of the fixed segments 35 of the distributor, the circuit is continued from said movable contact 36 through the fixed segment 35, connection 57 and primary of the high tension induction coil to ground at 59. When the higher portion of the cam 26 passes under the projection 25 of the arm 17, it raises the contact 20 momentarily out of contact with the fixed contact 21, opening the circuit above traced, and the self-induction coil 49 then sets up a self-inductive current of high potential in this circuit, charging the condenser 55, said condenser discharging through a circuit comprising the part of the circuit 48 connecting the condenser with the interrupter, the contacts of the interrupter and the spark gap therebetween, the contacts of the distributor and the primary coil of the high tension self-induction coil which has been selected for the time being by the distributor. The time at which this action 125 130

takes place is determined by adjustment of the interrupter by the controlling means 11 which shifts the position of the cam 26, and thereby determines the time at which the 5 projection 25 will ride over the high portions of said cam.

Assume now that the controlling member 11 has been moved so as to advance the interruption for producing the spark to the time 10 at which the distributor contact 36 has just passed onto one of the segments 35. The connection for the energizing circuit which is established by the distributor having been established at the very moment of interruption, there would be no opportunity for energization of the self-induction means in the charging circuit if it were not for the operation 15 of the supplementary connection through the self-induction coil 40 to ground. It will be noted that the connection from the rotary contact 36 of the distributor through this self-induction coil 40 to ground extends continually irrespective of the movement of the distributor, so that 20 there is always a path for the energizing current from the charging connection 48 even when the contact 36 of the distributor is on an insulating portion of the distributor, the current passing in that case from 25 the fixed contact 21 of the circuit interrupter to sleeve 38, bond 45, self-induction coil 40 and connection 44 to ground and thence back to the battery ground at 53. There is thus a circuit established for the current to 30 pass from the battery through the self-induction coil 49 and the charging circuit, and through this supplementary self-induction coil 40 before the contact 36 passes onto a distributor segment 35, so that when the 35 contact 36 does pass onto such a segment, the circuit may be immediately interrupted by the circuit interrupter and the main self-induction coil 49 will have been sufficiently preenergized to deliver the requisite discharge current. The inductance of the self-induction coil 40 is small compared with the inductance of the main self-induction coil 49, so that the interposition of said supplementary self-induction coil in the circuit 40 does not materially reduce the energy of the high tension current for charging the condenser. On the other hand, the inductance of said supplementary self-induction coil 40 is large compared with that of the high tension induction coil 58, so that the discharge 45 from the condenser on reaching the rotary contact 36 of the distributor passes almost wholly along the path through the high ten-

sion self-induction coil 58 to which it is connected for the time being by the distributor. 60

What I claim is:

1. In an ignition system, the combination of a source of electric current, a charging circuit connected thereto and including self-induction means, a plurality of discharge 65 connections, a distributor for establishing connection successively from said charging circuit to said discharge connections, an interrupter connected in the charging circuit, a condenser connected to the charging circuit, to receive a charge therefrom on interruption of said circuit, and to discharge through the discharge connections, means 70 for controlling the time of operation of said interrupter and a supplementary connection 75 for the charging circuit independent of the discharge connections through the distributor to enable energization of the charging circuit, precedent to the connection of the charging circuit to any given discharge connection by the distributor.

2. In an ignition system, the combination of a source of electric current, a charging circuit connected thereto and including self-induction means, a plurality of discharge 85 circuits, a distributor for establishing connection successively from said charging circuit to said discharge circuits, an interrupter connected in the charging circuit, a condenser connected to the charging circuit, to 90 receive a charge therefrom on interruption of said circuit and to discharge through the discharge circuits, means for controlling the time of operation of said interrupter and a supplementary connection for the charging 95 circuit, independent of the discharge connections through the distributor, to enable energization of the charging circuit precedent to the connection of the charging circuit to any given discharge connection by 100 the distributor, said supplementary connection for the charging circuit including self-induction means of lower inductance than the self-inductance means in the charging circuit and said discharge connections including high-tension induction devices of 105 lower inductance than the said supplementary connection.

In testimony whereof, I have hereunto set my hand at Los Angeles, California, this 9th 110 day of November 1910.

JAMES E. SEELEY.

In presence of—

ARTHUR P. KNIGHT,
